(57) **CLAIM**

The ornamental design for an interface dock, as shown and described.

DESCRIPTION

FIG. 1 is a front perspective of a interface dock showing my new design;

FIG. 2 is a top view thereof;

FIG. 3 is a bottom view thereof;

FIG. 4 is a left side view and right side view thereof;

FIG. 5 is a front view thereof; and,

FIG. 6 is a rear view thereof.

The broken lines immediately adjacent to the shaded areas form unclaimed boundaries of the design. The broken line showing a cartridge in the interface dock is for environmental purposes only and forms no part of the claimed invention. The broken line showing a recessed region, connector portions and the remainder of the interface dock is for environmental purposes only and forms no part of the claimed invention.

1 Claim, 4 Drawing Sheets
